DEVICE FOR CLEANING HARD RESIDUE
FROM TUBES BY RUPTURING SAID
RESIDUEPercival N. Bisson, Olympia, Wash., assignor, by
decree of distribution, to Ethel Mae Bisson

Application August 11, 1947, Serial No. 768,021

6 Claims. (Cl. 15—386)

1

My invention relates to a cleaner for the exterior surfaces of a cylindrical member. More particularly, my invention relates to the cleaning of cylindrical members as pipes, which have formed on the surfaces thereof a hard residue which can be ruptured or broken by pounding on such residue.

Many pipes, due to their use and environment, have scales of various residues on the surface and it is an object of my invention to remove such scale or residue and to clean the external surface of the pipes.

As an example of an environment in which my invention may be used, but not as a limitation thereof, my invention will be described in connection with its use in driers for wood veneer sheets which are later to be made into plywood.

In drying veneer sheets of wood, temperatures on the order of 300° F. are employed in a housing which is closed except for the opening to permit the introduction of veneer sheets and an exit for veneer sheets. The veneer sheets are supported by driven rollers positioned above and below the veneer and the rollers are commonly driven and in all cases are rotatably mounted. Due to the temperatures involved, wood exudes various substances as pitches and resins and the exudates or the reaction products of the exudates and heat become deposited on the rollers in the drier.

It is necessary to periodically remove the scale, foreign matter or coating on these rollers or else serious objections obtain. For example, the coating on the rolls may discolor the veneer sheets or it may build up the rollers to an extent where the passage way between rolls is limited and the veneer sheet is therefore marked.

Also, the presence of the wood exudates or the reaction products thereof and heat are inflammable and present a fire hazard. While other reasons may be cited for the necessity of maintaining the rollers substantially clean, it is now recognized that it is good engineering practice to periodically clean the rolls of a plywood drier at spaced periods in the order of one week.

While many practices have been suggested, the most practical practice heretofore employed was to steam clean the rollers and this at as close a period as possible to the time the drier was being laid up at the end of each working week.

Heretofore, it has been suggested that pounding of the rolls might be useful in cleaning the same. However, to my knowledge no device has been presented which will provide commercial results in cleaning veneer drier rollers.

2

In a veneer drier, it is not uncommon to have ten to twelve sections of drying units and where each section includes 50 to 90 rolls. These rolls are relatively closely spaced together and are in superposed levels. At each level there will be top and bottom rolls for the sheet of veneer which is supported and 5 to 7 level driers are commonly used.

It is an object of my invention to provide a rotatably mounted hammer head carrying revolvably mounted surface contacting hammers which are driven by an air motor.

It is a further object of my invention to provide an air motor with the exhaust thereof directed toward the surface being hammered so that upon rupture of the surface coating of the roll the exhaust air may be employed to drive off the ruptured surface coating. In other words, it is an object of my invention to blow off the loosened surface coating as soon as possible after a minimum of pounding.

It is another object of my invention to support the hammer head by rotatably mounted carriers which rest on adjacent rollers to be cleaned.

It is a further object of my invention to support the hammer head by rotatably mounted supporting means and to simultaneously clean two adjacent rollers and preferably from the upper and undersides of said rollers.

It is a further object of my invention to provide side thrust means so that the rotatably mounted hammer head can be maintained intermediate two adjacent rollers or maintained adjacent only one of said rollers.

The above mentioned general objects of my invention together with others inherent in the same are attained by the devices illustrated in the accompanying drawings, throughout which like reference numerals indicate like parts.

Figure 1 is a top plan view, with parts broken away, of a device embodying my invention, wherein the hammer elements are in retracted position;

Fig. 2 is a side elevation, with parts broken away, of the structure shown in Fig. 1 and with the hammer elements in extended position;

Fig. 3 is a sectional view taken substantially on broken line 3—3 of Fig. 1;

Fig. 4 is a view in elevation of the hammer elements in extended position and taken substantially on broken line 4—4 of Fig. 2;

Fig. 5 is a view in elevation, with parts in section, taken substantially on broken line 5—5 of Fig. 2; and

Fig. 6 is a view in end elevation of a modified

form of my invention relating particularly to a carriage member used where one of two adjacent cylindrical members is being cleaned.

A hose connector 7 connects to any suitable source of air under pressure. The hose connector 7 may be of any common type and can be readily obtained on the market. The hose connector 7 is preferably connected with a shut-off valve 8 to provide a self-contained unit so it will be unnecessary to be limited to a source of air under pressure having a readily available shut-off means. A carriage member is provided which may include standard water or steam pipe 9. The longitudinally extending pipe 9 has secured thereto two supports, as pipes 10 and 11, which extend laterally from the pipe 9. The pipes 10 and 11 can be connected with the pipe 9 by any suitable manner as by welding as indicated in Fig. 1.

The pipes 10 and 11 rotatably mount sleeves 12 and 13, which preferably have knurled surfaces, and the said sleeves are retained in place by any suitable means, such as holes 14 and 15 and cotter pins passing therethrough (the cotter pins are not shown). Transverse restraining means 16 and 17 are employed to resist transverse movement of the carriage as the hammers (hereinafter described) pound against adjacent pipes. The length of the restraining means 16 and 17 will depend upon the type and nature of the drier, concerning which the rolls thereof are to be cleaned. A way of securing the restraining means 16 and 17 to the pipe 9 is by welding the same to the side of the pipe 9 as indicated in Figs. 1 and 2.

The carriage includes not only the parts 9 to 17 inclusive, but members 19 to 26 inclusive. The side outlet T 18 is positioned with the side outlet projecting downwardly. The aligned openings of the T project laterally and the other opening of the T projects longitudinally of and connects with the pipe 9. The side outlet T 18 is connected with the pipe 9, rods 19 and 20 and sleeves 21 and 22. The sleeves 12-13 and 21-22 are thus rotatably mounted on the pipe or carriage 9 and the sleeves 12-13 are longitudinally spaced as respects the sleeves 21-22 and thus such sleeves function as longitudinally spaced roller supports carried by said carriage member 9, extend laterally on both sides of said carriage member 9, and are adapted to rest upon two adjacent cylindrical members to be cleaned.

It is to be understood that my invention is not to be limited to the use of the side outlet T 18 as I may weld rods 19 and 20 to pipe 9 as was indicated in connection with pipes or rods 10 and 11 to pipe 9. If a side outlet T 18 is employed, its lateral openings must be plugged against the escape of air and I thus have indicated plugs 23 and 24, which plug the said lateral openings and at the same time support the rods 19 and 20.

The sleeves 21 and 22, which preferably have knurled surfaces, are rotatably mounted on rods 19 and 20 and they are held in place by holes 25 and 26 and cotter pins passing through said holes (said cotter pins not being shown). The side outlet of the side outlet T 18 is preferably connected to a nipple 27 to provide for suitable adjustment in length of the hammer head below the elevation of the carriage. In other words, the relative elevation of the hammer head to the carriage can be adjusted by providing a coupling or nipple 27 of desired length. The coupling 27 connects with an elbow 28 which is coupled to

an air driven motor 29. From the parts thus described, it will be obvious that air entering coupling 7 passes through shut-off valve 8, through pipe 9, through side outlet T 18, through coupling 27, through elbow 28 and to air motor 29.

The internal structure of air motor 29 forms no part of this invention and hence the same is diagrammatically illustrated. However motor 29 is of a construction so that by the use of air under pressure rotary motion of the shaft 30 obtains. Also, the exhaust or exhaust ports 31 (see Figs. 1 and 5) generally direct air against the surface being hammered. Thus, the air is utilized for the purpose of driving motor 29 and the exhaust air from said motor 29 is utilized in the cleaning action.

The hammer head which I desire to use in my invention embodies plates 32 and 33 which are held in suitably spaced relation by shouldered studs 34 which shouldered studs 34 carry reduced threaded end portions 35 and nuts 36 thereon. Each stud 34 supports a tubular hammer 37 and the plates 32 and 33 are held sufficiently spaced between studs 34 so as not to limit radial movement of the tubular hammers 37. Preferably the corners of the hammers 37 are cut away, as best shown in Figs. 1 and 2, to reduce the effective pounding area and, at the same time, not to substantially reduce the mass of the hammer. Also, such cutting away of the hammer 37 eliminates sharp corners and possible damage to the cylindrical members on the pipes being cleaned.

In the use of the construction shown in Figs. 1 to 5 inclusive of the drawings, the sleeves 12, 13, 21 and 22 are supported on two adjacent cylindrical members as two adjacent rolls in a veneer drier. The restraining means 16 and 17 are of a length to limit side movement of the device as the device is caused to move longitudinally of the pipes to be cleaned. As the air motor is driven, the hammers 37 move radially, for example, from the position shown in Fig. 3 toward or to the position shown in Fig. 4, and said hammers 37 will contact and pound the surfaces to be cleaned, and preferably from a position to one side of the center line of the pipe being cleaned. By having the hammers act on surfaces of the rolls to one side of the center line, it is possible to clean four rolls at a time, two adjacent rolls above and two adjacent rolls below the hammer head. At the same time, preferably the rolls to be cleaned are driven so that all of their surfaces are uniformly exposed to the hammer action of the hammers 37. At the same time that a particular surface is being hammered, the exhaust air from the air motor 29 will be directed toward the surfaces being hammered and by the conjoint action of the hammers rupturing the film and by the air blowing against such ruptured film, there is a rapid and efficient cleaning of cylindrical surfaces, as drier rolls having deposits thereon.

Preferably, my device when employed for cleaning veneer drier rolls, is employed about eight hours after the veneer drier has been shut down. This leaves time enough for the wood exudates or heat reaction products thereof, to set and form a film of the best characteristics for removal by my device. In other words, the film is not so hard that it will become powdery by a pounding action and require pounding of each and every minute surface area, and the film is of a character so it can become ruptured and so air will augment the cleaning action. If my

device is used directly after the drier has been shut down, then the surface coating on the rolls of the veneer drier is somewhat tacky or viscous. On the other hand, if too long a period of time is allowed to elapse then the film becomes tough, tightly bound to the rollers and tends to powder rather than rupture.

Referring to Fig. 6 of the drawings, an alternative construction of my invention is shown. This is a view in end elevation and will correspond to a view taken from the right of either Fig. 1 or Fig. 2, and looking toward the left. The pipe 9, plugs 23 and 24, side opening elbow 18, rod 19, sleeve 21, hole 25, plate 33, hammers 37, reduced end portions 35 and nuts 36 may be duplicates of the parts bearing similar numbers in the previous figures and therefore are given similar numbers. Also, the rod 20 may be similar to the rod 20 of the previous figures and is therefore given a similar number. In Fig. 6 I have shown an attachment which is secured to the rod 20 so that the device may be used to clean one of two adjacent rolls rather than cleaning both of said adjacent rolls or the device may be used to clean two rolls, one above the other rather than four adjacent rolls. This attachment comprises a pipe or sleeve 38 which is longitudinally slidably adjustable relative to pipe 20 as by means of bolt 39 and lock nut 40. Means are carried by the sleeves 38 so that a thrust can be exerted against one of two adjacent pipes and the other of said pipes may be cleaned. This thrust member may comprise an elbow 41, nipple 42, a T 43, a pipe 44, a pipe 45, an elbow 46 and a pipe 47. The pipes 44, 45 and 47 rotatably carry sleeves 48, 49 and 50. Preferably sleeves 48, 49 and 50 have knurled surfaces similar to sleeves 12, 13, 21 and 22. The sleeves 48 and 50 may be held on pipes 44 and 47 by holes 50 and 51 and cotter pins passing therethrough (not shown). A yoke is provided by sleeves 48, 49 and 50 to encompass one of two adjacent pipes which serves as a thrust member and the other adjacent pipe supports sleeve 21. Thus the sleeves 48 and 50 function as "lateral thrust resisting means connected with said carriage member 9 and contacting at least one of said cylindrical members (a cylindrical member to be cleaned)." By adjustment of the set screw 39 and lock nut 40, suitable support may be provided so that the hammer head comprising hammers 37 will hammer one of said two adjacent rolls. At the same time, the exhaust from the motor 29 will be directed generally against the surfaces being hammered. The same mode of operation of the device of the previous figures will obtain when the accessory of Fig. 6 is employed except that only one of two laterally spaced adjacent rolls is being hammered rather than both thereof and also two vertically spaced rolls may be hammered.

Obviously, changes may be made in the forms, dimensions and arrangements of the parts of my invention without departing from the principle thereof, the above setting forth only preferred forms of embodiments of my invention.

I claim:

1. A cleaner for the external surfaces of adjacent substantially horizontal cylindrical members comprising an elongated carriage member adapted to lie substantially parallel to the axes of the cylindrical members being cleaned; longitudinally spaced roller supports carried by said carriage member, extending laterally on both

sides of said carriage member, and adapted to rest upon two adjacent cylindrical members; a vertically offset supporting member carried by said carriage member; a rotary hammer head, means to rotate said hammer head, said hammer head being carried by said offset supporting member and having its axis of rotation substantially parallel to the longitudinal axis of the carriage member; and a rotary hammer carried by said rotary hammer head and mounted radially of the center of rotation of the rotary hammer head.

2. A cleaner for the external surfaces of adjacent substantially horizontal cylindrical members comprising an elongated carriage member adapted to lie substantially parallel to the axes of the cylindrical members being cleaned; supporting means carried by said carriage member, extending laterally on both sides of said carriage member, and adapted to rest upon two adjacent cylindrical members; lateral thrust resisting means carried by said supporting means and contacting at least one of said cylindrical members; a hammerhead supporting means carried by said carriage member; a rotary hammerhead, means to rotate said hammerhead, said hammerhead being carried by said hammerhead supporting member and having its axis of rotation substantially parallel to the longitudinal axis of the carriage member; and a rotary hammer carried by said rotary hammerhead and mounted radially of the center of rotation of the rotary hammerhead.

3. A cleaner for the external surfaces of adjacent substantially horizontal cylindrical members comprising an elongated carriage member adapted to lie substantially parallel to the axes of the cylindrical members being cleaned; supporting means carried by said carriage member, extending laterally on both sides of said carriage member, and adapted to rest upon two adjacent cylindrical members; lateral thrust resisting means connected with said carriage member and contacting at least one of said cylindrical members; a hammerhead supporting means carried by said carriage member; a rotary hammerhead, means to rotate said hammerhead, said hammerhead being carried by said hammerhead supporting member and having its axis of rotation substantially parallel to the longitudinal axis of the carriage member; and a rotary hammer carried by said rotary hammerhead and mounted radially of the center of rotation of the rotary hammerhead.

4. A cleaner for the external surfaces of four substantially horizontal cylindrical members spaced substantially about a common center with two thereof in one horizontal plane and the other two in a horizontal vertically spaced plane comprising an elongated carriage member adapted to lie substantially parallel to the axes of the cylindrical members being cleaned; supporting means carried by said carriage member, extending laterally on both sides of said carriage member, and adapted to rest upon the upper two cylindrical members; a downwardly vertically offset supporting member carried by said carriage member; a rotary hammerhead, means to rotate said hammerhead, said hammerhead being carried by said offset supporting member and having its axis of rotation substantially parallel to the longitudinal axis of the said common center about which are spaced said cylindrical members; and a rotary hammer carried by said rotary hammerhead and mounted radially of the center of rotation of the rotary hammerhead.

head, whereby to clean simultaneously all said four cylindrical members.

5. A cleaner for the external surfaces of adjacent substantially horizontal cylindrical members comprising an elongated carriage member adapted to lie substantially parallel to the axes of the cylindrical members being cleaned; supporting means carried by said carriage member, extending laterally to at least one side of said carriage member, and adapted to rest upon at least one of said cylindrical members; a vertically offset supporting member carried by said carriage member; a rotary hammerhead, means to rotate said hammerhead, said hammerhead being carried by said offset supporting member and having its axis of rotation substantially parallel to the longitudinal axis of the carriage member; and a rotary hammer carried by said rotary hammerhead and mounted radially of the center of rotation of the rotary hammerhead.

6. A cleaner for the external surfaces of adjacent substantially horizontal cylindrical members comprising a first pipe adapted to be connected at one end portion with a source of air under pressure and adapted to lie substantially parallel to the axes of the cylindrical members being cleaned; supports carried by said first pipe, extending laterally to at least one side of said first pipe, and adapted to rest upon at least one

5 of said cylindrical members; a vertically offset second pipe connected with said first pipe; an air driven motor connected with said second pipe and having its axis of rotation substantially parallel to the longitudinal axis of said first pipe; a rotary hammerhead connected to said air driven motor; a rotary hammer connected with said rotary hammerhead and with the exhaust of said motor directed toward the cylindrical surface being hammered.
